UNITED STATES PATENT OFFICE

JOHN LIPPERT, OF CHICAGO, ILLINOIS

REPLACEABLE HEEL FOR SHOES

Application filed March 3, 1930. Serial No. 432,889.

The invention relates to heels for shoes and especially to exchangeable heels made from rubber or the like. The object of the invention is to provide a rubber heel with means for easily and quickly attaching the heel to the shoe.

Another object of the invention is to provide the shoe with means adapted to co-operate with the above mentioned means for making it possible to remove a worn heel from the shoe and for replacing it with a new heel.

Other objects of the invention not specifically mentioned may be easily understood and ascertained from the following description in connection with the accompanying drawings forming a part thereof. It is however to be noted, that the invention is not to be restricted or limited to the exact construction or formation, shown in the drawings and described in the specification, but that the invention is only to be limited by the scope of the claims appended hereto.

In the drawings illustrating a preferred embodiment of the invention:

Fig. 1 is a bottom view of a holder adapted to be fastened to the heel portion of the sole of a shoe and adapted to removably receive an exchangeable heel according to the present invention.

Fig. 2 is a bottom view of a heel according to the present invention provided with means adapted to cooperate with the holder shown in Fig. 1 for adjusting and holding a heel in position.

Fig. 3 is a sectional view taken on line 3—3 of Fig. 1.

Fig. 4 is a side view of Fig. 2.

Fig. 5 is a cross section of a assembly of the holder shown in Figs. 1 and 3 and the heel shown in Figs. 2 and 4, and

Fig. 6 is a side view of the assembly of the holder and the heel.

The holder may be made from any suitable material and has the outline of a heel as shown in Fig. 1 and is adapted to be attached permanently in any suitable way to the heel portion of a shoe.

The holder is to be fastened to the shoe with the surface 7 abutting the sole of the

shoe and from the body portion 8 of the shoe a circumferential flange 9 extends downwardly. In this flange a groove 10 is formed for the purpose to be described later on and at the rearward end a shallow opening 11 extends through the flange 9 and communicates at one end with the groove 10 and at the other end with the atmosphere. The flange 9 is provided with an offset or a shoulder 12 as indicated in the drawings, so that a depression 13 is formed on the lower surface of the holder.

The heel according to the present invention consists actually of two parts. One part is preferably made from rubber and has the shape common to rubber heels with the exception, that said heel is not quite as high as the usual rubber heel. On the lower surface 14 of said heel a plurality of knobs 15 or the like are provided, which are common with the old kind of rubber heels. The outline of the lower portion 16 of the rubber heel is such, that it fits exactly on the outline of the holder described above. A shoulder 17 is formed on the upper surface of the heel portion by a circumferential flange 18, extending upwardly from the heel portion and being arranged somewhat inwardly from the outer rim of the heel. A rib 19 extends also upwardly from the upper surface and is arranged in the longitudinal center of the heel.

A plate 20 is fastened to the heel portion by means of rivets 21 or the like, in such a manner, that the upper surface of the circumferential flange 18 and the rib 19 abuts the lower surface of the plate 20. The rivets 21 preferably extend through the knobs 15 mentioned above.

The plate 20 is provided at its rearmost part with a tongue 22 and the outline of the plate is such, that it fits snugly into the groove 10. The tongue 22 will extend through the shallow opening 11 in the holder and may then be bent upwardly as indicated in Fig. 6 to prevent the plate from accidentally sliding out of the groove 10. The height of the circumferential flange 18 and the rib 19 is such, that the upper surface of the shoulder portion 17 on the heel 16 will firmly abut the lower surface of the circumferential flange 18.

9 of the holder when the plate 20 is inserted into the groove 10 of the holder.

As indicated in Fig. 5 air spaces 23 are formed between the plate 20 and the heel 5 whereby the resiliency of the heel is increased.

It is easy to see, that a heel according to the present invention may be easily and quickly attached and removed to or from a shoe, provided with the holder co-operating 10 with said heel.

When the holder is fastened to the heel portion of the sole of a shoe, it is only necessary to slide the plate 20 into the groove 10 and clinch the tongue 22 to prevent the heel from 15 slipping forwardly in order to fasten the heel to the shoe. As long as the tongue is clinched, the heel will be held securely and firmly in position, but by straightening the tongue 12 it is possible to remove the heel 20 by simply sliding it forwardly out of the groove 10.

Having described my invention and how the same is to be performed, I claim as new and desire to secure by Letters Patent:

25 1. In a device of the class described a rubber heel having a circumferential ledge formed on its upper surface and a plate fastened to the upper surface of the heel, extending beyond the circumference of the ledge, the 30 heel proper extending beyond the circumference of the plate, said plate having a tongue extending rearwardly beyond the circumference of the body of the heel.

2. In a device of the class described, a heel, 35 a circumferential flange on the upper surface of said heel, arranged inwardly of the circumference of the heel, extending parallel to said circumference and forming a ledge on the upper surface, a rib extending on the longitudinal center of the heel, formed on the upper surface thereof and having the same height as the circumferential flange and a plate firmly fastened to the heel and abutting the circumferential flange and the rib, and extending 40 somewhat beyond the outer circumference of said flange, but being of smaller dimensions than the outer circumference of the heel proper, said plate having a tongue extending rearwardly beyond the circumference 45 of the body of the heel.

3. In combination with a rubber heel having a body portion, a circumferential flange on the upper surface of said body portion and forming a ledge therewith, a plate firmly 55 attached to the heel above the circumferential flange, having the same outline as the circumference of the body portion, but of smaller dimensions and extending beyond the outer circumference of the circumferential 60 flange, a holder adapted to be fastened to the rear portion of a shoe, having the same outline as the body portion of the heel and provided with a groove adapted to receive the plate fastened to the body of the heel, said 65 holder to be provided with a rearwardly ex-

tending opening, and a tongue on said plate adapted to be received by said opening, extending beyond the same and adapted to be clinched against the outer circumference of the holder.

In witness whereof I affix my signature.

JOHN LIPPERT.
